DRAWSTRING ATTACHABLE COVER

Joseph H. Moss, Mount Vernon, N. Y.

Application September 22, 1942, Serial No. 459,281

6 Claims. (Cl. 2—197)

My invention relates to improvements in draw string attachable covers for objects such as bowls, heads, or the like, having a substantially circular periphery at a portion of the outer surface thereof. It is particularly adapted for objects of the type having a uniform periphery at this point, such as a bowl or head.

My invention comprises a modification of former types of covers employed for this purpose so as to make such a cover capable of functioning with a draw string. An object of my invention is to provide a cover of this type employing a simple draw string rather than an elastic to retain it in position.

My invention is particularly adapted for use on objects which are desired to be both air and moisture proof, such as bathing caps or covers for dishes or bowls containing food.

A further object of my invention is to provide a simple draw string attachable cover in which the draw string will slide freely while being attached but which will grip with friction to retain the cover to the object, preferably in both an air and moisture impervious manner.

A further feature of my invention relates to improvements in the method of making such a draw string attachable cover.

These and such other objects of my invention as may hereinafter appear will be best understood from a description of the accompanying drawings which illustrate various embodiments thereof and steps in their method of manufacture.

In the drawings,

Fig. 1 is a plan view of a flat unused draw string attachable cover constructed in accordance with my invention, in which the ends of the draw string substantially coincide with the ends of the tab.

Fig. 2 is a plan view of a different embodiment of my invention in which the draw string has free ends projecting beyond the end of the tab.

Fig. 3 is an edge elevation of the embodiment of my invention shown in Fig. 1.

Fig. 4 is a large detail perspective view illustrating the ends of the cover tab and draw string of the embodiment shown in Fig. 1.

Fig. 5 is a side elevation of my improved cover in use as a bowl cover.

Fig. 6 is a perspective view of my improved cover in use as a bathing cap.

Figs. 7 to 11 illustrate steps in the method of manufacturing my improved cover.

Fig. 7 is a plan view of a blank piece of fabric of a shape suitable for forming my improved

cover, of a generally circular shape and having an integral tab.

Fig. 8 is a plan view diagrammatically illustrating the steps of simultaneously applying and 5 sewing the piping to the peripheral edge of the cover and simultaneously inserting the draw string, from one side edge of the tab.

Fig. 9 is a perspective view of a modified type 10 of sewing machine performing the steps diagrammatically illustrated in Fig. 8.

Fig. 10 is a perspective view of the tab portion 15 of the cover illustrating the final step of applying and sewing the piping to the opposite side edge of the tab, by relatively rotating said fabric piece to cause the upper and lower edge of the last laid and sewed piping end to overlie the respective upper and lower edge of the first laid and sewed piping end with the single line of stitching crossing itself adjacent the tip of tab 20 to restrict the area of the ends of the thus formed piping channel on each side of said tab adjacent said tab tip and the step of simultaneously cutting off the continuous piping and draw string ends just beyond the tip of the fabric piece tab.

Fig. 11 is a perspective view similar to Fig. 10 25 showing the infolded ends of the piping and the ends of the draw string in the piping channel in the completed cover.

In the drawings, wherein like characters of 30 reference generally indicate like parts throughout, 10 generally indicates a cover for an object such as a bowl, head or the like having a substantially circular periphery at a portion of the outer surface thereof which preferably remains 35 constant, such as in a standard bowl or dish or a human head. While my cover 10 may be constructed of any type of fabric, it preferably comprises a fabric which is not only moisture proof but which also may, if desired, be air proof and 40 may comprise rubber, Cellophane or any suitable type of waterproofed freely flexible fabric. My improved cover 10 comprises a substantially circular member or piece 12 preferably of air and moisture impervious fabric, having an integral tab 14 projecting therefrom, having a pointed tip 16 and edges 18^a and 18^b merging with the peripheral edge 20 of said member or piece 12, piping 22 sewed to said member from one side edge 18^a of said tab portion as at 24, around the peripheral edge 20 of said member to the other side edge 18^b of said tab with the line of stitching 24 crossing itself as at 26 adjacent the tip 16 of said tab portion 14 to restrict the area of 45 each end of said piping 22 as at 27, whereby when said draw string is drawn tight the ends thereof

are restricted from sliding within the restricted ends 27 of said piping.

While the piping 22 may be formed in any suitable manner, it preferably comprises a narrow strip of binding fabric 32 folded substantially centrally thereof as at 38 with each respective thus formed upper and lower edge 34 and 36 thereof respectively overlying and underlying the edge 20 of said cover 12 and the center 38 slightly spaced from the edge 20 of said cover to form the piping channel 40 extending from one side edge 18^a of said tab with the edges of one end 42^b of said binding overlapping the edges of the other end 42^a of said binding adjacent the tip 16 of the tab 14 and the draw string 28 of at least the length of said piping or binding 22 contained within said thus formed piping channel 40 exterior of the edge 20 of said cover and a line of stitching 24 extending through each overlying and underlying edges 34 and 36 of said binding and adjacent cover portion 21 from each side edge of said tab tip 18^a and 18^b, crossing itself adjacent said tip as at 26 to restrict the area of said piping channel 40 at each end 27 adjacent said tab tip 16.

It is thus obvious with this construction that when said cover 10 is laid over any object with the piping edge 22 thereof adjacent said portion of circular periphery 46 and said draw string 28 drawn tight, the ends 39 of said draw string 28 may be retained by friction in the restricted ends 27 of said piping channel 40 to retain said cover 10 in substantially air and moisture proof relationship on said object.

I have illustrated in Fig. 5 my improved cover in use as an air and moisture impervious cover for a bowl 44, the draw string being tightened around the circular periphery 46 of the bowl. It is thus obvious that my improved cover being air and moisture proof is of a type that will keep food free from air and moisture in the bowl and is of a type often used for storing food in refrigerators.

I have shown my improved cover 10 in Fig. 6 employed as a cap for the head 48 of a human being, and it is apparent that this provides an ideal head covering such as a cap, beret, etc., and one which, since it may be readily constructed to be moisture proof, makes an ideal bathing cap.

While my improved cover may be constructed in any suitable manner, it may be conveniently constructed as follows: I preferably cut a piece of fabric into a generally circular shape 12, greater than the periphery about which the draw string is to operate on the object and with an integral tab 14 projecting from a portion thereof having a pointed tip 16 and edges 18^a and 18^b merging with the peripheral edge 20 of said fabric piece. I may, if desired, infold the edges 35 of a continuous narrow strip of binding fabric 32, as at 37, and in any event fold it centrally thereof as at 38 and guide the folded upper and lower edges 34 and 36 thereof respectively above and below the peripheral edge 20 of said fabric piece 12 and the folded center portion 38 thereof a spaced distance from said peripheral edge, and I also sew said upper and lower folded edges 34 and 36 adjacent fabric piece portion 21 together by the stitching 24 to form the piping channel 40 and draw a draw string 28 within said piping channel 40 from said tab edge 18^a to the tab edge 18^b, while relatively rotating said fabric piece 12 to cause the upper and lower edges of said last laid and sewed piping end 42^b to overlie

the respective upper and lower edges of the first laid and sewed piping end 42^a with the single line of stitching 24 crossing itself as at 26 adjacent the tip 16 of the tab 14 to restrict the area 27 of the ends of the thus formed piping channel 40 on each side of said tab 14 adjacent said tab tip 16 and I then cut off the continuous piping and draw string ends just beyond the tip 16 of the fabric piece tab 14 as shown in Figs. 10 and 11. While these aforesaid steps may be done by hand or machine successively or simultaneously, I preferably continuously infold the edges 35 of the continuous binding strip of narrow fabric 32, as at 37, simultaneously fold them centrally as at 38 and guide the folded upper and lower edges 34 and 36 thereof respectively above and below the peripheral edge 20 of said fabric piece 12 and the folded center portion 38 a spaced distance from said peripheral edge and simultaneously sew said edges to said fabric piece as at 24 to form the piping channel 40 in the manner previously described and simultaneously insert the draw string 28 within said piping channel 40 as formed. For this purpose I preferably 25 employ a continuous narrow strip of binding fabric 32 and a continuous draw string 28 and apply them from beyond one side edge 18^a of said tab to beyond the other edge 18^b, and for this purpose use the roll of binding 32' to continuously supply the binding 32 and the spool 28' to continuously supply the draw string 28.

I have shown in Fig. 9 a suitable attachment for a sewing machine for simultaneously sewing the piping 22 around the peripheral edge 20 of the cover 12 and inserting the draw string 28 within the piping. For this purpose a guide 50 may be provided of a general type shown in Patent No. 1,756,036, issued to Seaman and Braf on April 29, 1930, which may, if desired, in addition to folding the piping 22 as at 38 and applying it to the peripheral edge 20 of the relatively rotated cover 12 adjacent the sewing needle 52, may also simultaneously infold the edges 35 of the respective piping edges 34 and 36, as at 37, while it is being applied, to prevent unraveling, as the cover 12 is being relatively rotated around the needle 52 and as the draw string 28 is being simultaneously drawn into the piping channel 40 as the piping 22 is formed.

Employing the method hitherto described will produce the embodiment of cover 10 shown in Fig. 1, with the ends 27 of the draw string substantially flush with the ends of the piping channel 40. If desired, by suitable modification of 55 the method hitherto described, the ends 39 of said draw string may extend beyond the ends of said piping as in the embodiment of my invention shown in Fig. 2. It is apparent, however, that with the embodiment of my invention shown in Fig. 1, the ends of the draw string may be readily grasped and pulled to draw the edge of the cover 10 around the periphery 46 of the object 44 or 48 and that the constricted portions 27 in the ends of the piping channel 40 will bind the ends of the draw string 28 so as to retain the cover 10 in an attached substantially air and moisture proof condition on the object.

It is apparent, therefore, that I have provided a novel type of draw string attachable cover and method of making the same with the advantages explained above.

It is understood that my invention is not limited to the specific embodiments shown or methods described and that various deviations

may be made therefrom without departing from the spirit and scope of the appended claims.

What I claim is:

1. A cover for an object such as a bowl, head or the like, having a substantially circular periphery at a portion of the outer surface thereof, comprising a substantially circular member of air and moisture impervious fabric, having an integral tab projecting therefrom having a pointed tip and edges merging with the peripheral edge of said member, a piping forming binding comprising a narrow strip of fabric having infolded unravelable edges and folded substantially centrally thereof with each upper and lower edge thereof respectively overlying and underlying the edge of said cover and the center thereof slightly spaced from the edge of said cover to form a piping channel extending from each side edge of said tab with the edges of one end of said binding overlapping the edges of the other end of said binding adjacent the tip of the tab, a draw string of at least the length of said binding contained within said thus formed piping channel exterior of the edge of said cover and a line of stitching extending through each infolded overlying and underlying edge of said binding and adjacent cover portion from each side edge of said tab tip crossing itself adjacent said tip to restrict the area of said piping channel at each end of said piping channel adjacent said tab tip whereby when said cover is laid over said object with the piped-edge thereof adjacent said portion of circular periphery and said draw string drawn tight, the ends of said draw string may be retained in the restricted ends of said piping channel to retain said cover in substantially air and moisture proof relationship on said object.

2. A cover for an object such as a bowl, head or the like, having a substantially circular periphery at a portion of the outer surface thereof, comprising a substantially circular member of air and moisture impervious fabric, having an integral tab projecting therefrom having a pointed tip and edges merging with the peripheral edge of said member, a piping forming binding comprising a narrow strip of fabric having edges folded substantially centrally thereof with each upper and lower edge thereof respectively overlying and underlying the edge of said cover and the center thereof slightly spaced from the edge of said cover to form a piping channel extending from each side edge of said tab with the edges of one end of said binding overlapping the edges of the other end of said binding adjacent the tip of the tab, a draw string of at least the length of said binding contained within said thus formed piping channel exterior of the edge of said cover and a line of stitching extending through each overlying and underlying edge of said binding and adjacent cover portion from each side edge of said tab tip crossing itself adjacent said tip to restrict the area of said piping channel at each end of said piping channel adjacent said tab tip whereby when said cover is laid over said object with the piped-edge thereof adjacent said portion of circular periphery and said draw string drawn tight, the ends of said draw string may be retained in the restricted ends of said piping channel to retain said cover in substantially air and moisture proof relationship on said object.

3. A cover for an object such as a bowl, head or the like, having a substantially circular periphery at a portion of the outer surface thereof,

comprising a substantially circular member of air and moisture impervious fabric, having an integral tab projecting therefrom having a pointed tip and edges merging with the peripheral edge of said member, piping sewed to said member from one side edge of said tab around the peripheral edge of said member to the other side edge of said tab with the line of stitching crossing itself to restrict the area of each end of said piping adjacent the tip of said tab portion and a draw string contained within said piping whereby when said draw string is drawn tight the ends thereof are restrained from slipping within the restricted ends of said piping.

4. The method of making a draw-string attachable cover for an object having a substantially circular periphery at a portion of the outer surface thereof, which comprises cutting a piece of fabric into a generally circular shape greater than said periphery of the object to be covered and with an integral tab projecting from a portion thereof having a pointed tip and edges merging with the peripheral edge of said fabric piece, continuously infolding the edges of a continuous narrow strip of binding fabric, simultaneously folding it centrally thereof and guiding the folded upper and lower edges thereof respectively above and below the peripheral edge of said fabric piece, and the folded center thereof a spaced distance from said peripheral edge, simultaneously sewing said upper and lower folded edges and adjacent fabric piece portion together to form a piping channel and simultaneously drawing a continuous draw string within said piping channel as formed, from beyond one side edge of said tab to beyond the other, while relatively rotating said fabric piece to cause the upper and lower edge of the last laid and sewed piping end to overlie the respective upper and lower edge of the first laid and sewed piping end with the single line of stitching crossing itself adjacent the tip of the tab to restrict the area of the ends of the thus formed piping channel on each side of said tab adjacent said tab tip and simultaneously cutting off the continuous piping and draw string ends just beyond the tip of the fabric piece tab.

5. The method of making a draw-string attachable cover for an object having a substantially circular periphery at a portion of the outer surface thereof, which comprises cutting a piece of fabric into a generally circular shape greater than said periphery of the object to be covered and with an integral tab projecting from a portion thereof having a pointed tip and edges merging with the peripheral edge of said fabric piece, folding a continuous narrow strip of binding fabric centrally and guiding the folded upper and lower edges thereof respectively above and below the peripheral edge of said fabric piece, and the folded center thereof a spaced distance from said peripheral edge, sewing said upper and lower folded edges and adjacent fabric piece portion together to form a piping channel and simultaneously drawing a continuous draw string within said piping channel as formed, from beyond one side edge of said tab to beyond the other, while relatively rotating said fabric piece to cause the upper and lower edge of the last laid and sewed piping end to overlie the respective upper and lower edge of the first laid and sewed piping end with the single line of stitching crossing itself adjacent the tip of the tab to restrict the area of the ends of the thus formed piping channel

on each side of said tab adjacent said tab tip and simultaneously cutting off the continuous piping and draw string ends just beyond the tip of the fabric piece tab.

6. The method of making a draw-string attachable cover for an object having a substantially circular periphery at a portion of the outer surface thereof, which comprises cutting a piece of fabric into a generally circular shape greater than said periphery of the object to be covered and with an integral tab projecting from a portion thereof having a pointed tip and edges merging with the peripheral edge of said fabric piece, folding a narrow strip of binding fabric centrally and guiding the folded upper and lower edges thereof respectively above and below the

5 peripheral edge of said fabric piece, and the folded center thereof a spaced distance from said peripheral edge, sewing said upper and lower folded edges and adjacent fabric piece portion together to form a piping channel from one side edge of said tab to the other, while relatively 10 rotating said fabric piece to cause the upper and lower edges of the last laid and sewed piping end to overlie the respective upper and lower edges of the first laid and sewed piping end with the single line of stitching crossing itself adjacent the tip of the tab to restrict the area of the ends of the thus formed piping channel on each side of said tab adjacent said tab tip and providing a draw string within said piping channel.

JOSEPH H. MOSS.
